(57) **CLAIM**

The ornamental design for a cosmetic jar as shown and described.

DESCRIPTION

FIG. 1 is a perspective view of a cosmetic jar, showing our new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the drawings depict portions of the cosmetic jar that form no part of the claimed design.
